UNITED STATES PATENT OFFICE.

ANDREW J. LIVESAY, OF WHITE SULPHUR SPRINGS, WEST VIRGINIA.

FOLDING RACK OR HOLDER.

Application filed January 9, 1928. Serial No. 245,568.

This invention relates to a folding rack or holder for various articles, the general object of the invention being to form the rack of wire and to hingedly connect to the bottom thereof a yoke-shaped member for holding papers, towels and the like.

Another object of the invention is to provide means for holding the device in folded position, with the yoke-shaped member folded against the device so that the device will occupy but little space when not in use.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a perspective view of the device in open position.

Figure 2 is a section on line 2—2 of Figure 1.

As shown in these views, the device consists of a rectangular frame 1 having its corners looped to form the upper eyes 2 and the lower eyes 3, these lower eyes being bent at rightangles to the frame. Horizontal wires 4 and vertical wires 5 have their ends looped around the sides and ends of the frame 1 with the vertical wires wrapped around the horizontal wires.

A front frame 6 is formed similar to the frame 1, this frame also having the horizontal wires 7 and the vertical wires 8 attached thereto, but the lower horizontal part of this frame 6 is netted and the end pieces of said frame 6 have eyes 9 at their lower ends for engaging the eyes 3 of the frame 1 and the lower ends of the vertical wires 8 of said frame 6 are looped around the bottom piece of the frame 1 so that said frame 6 is hingedly connected with the lower part of frame 1.

A wire 10 is movably connected with each of the eyes 3 by having an eye 11 formed at its lower end for engaging the eye 3 and the upper ends of these wires 10 are bent to form eyes 12. A wire 13 connects each of the eyes 2 with the eyes 12, each wire 13 having its ends bent to form eyes, one engaging the eye 2 and the other the eye 12. A

wire 14 connects the upper end of each wire 10 with each eye 15 formed at each upper corner of the frame 6, this wire 14 also having its ends bent to form eyes for engaging the eyes 12 and 15. Wires 16 connect each wire 10 with each end of the frame 1 and similar wires 17 connect each wire 10 with each end piece of the frame 6. These wires have their ends looped so that they are hinged to the end pieces and to the wires 10. Vertical wires 18 are spaced midway between each wire 10 and the end pieces of the frame 1 and 6, these wires 18 having their ends looped around the horizontal wires forming the end pieces of the device. Thus it will be seen that the wires 10 can be swung inwardly so as to fold the two sections of each end of the device to permit the frame 6 to be folded against the frame 1 to collapse the device. Each end of the device, when open, is of V-shape so that the frame 6 slopes upwardly and outwardly from the frame 1 when said frame is in a vertical position so that various articles can be placed in the device.

A yoke-shaped member 19 is hingedly connected with the bottom of the device by having eyes 20 formed at its upper end for engaging the eyes 3 of the frame 1. Thus this member can be swung upwardly against the folded device when the device is not in use. A latch 20' is hingedly connected with the top piece of the frame 1 to engage the folded parts to hold them in collapsed condition and a stem 21 is formed in the center of the top piece of the frame 1 by looping and twisting a portion of said top piece, this stem being formed with an eye 22 so that the device can be hung on a nail or other support on a wall.

It is thought from the foregoing description that the advantages and novel features of my invention will be readily apparent.

It is to be understood that I may make changes in the construction and in the combination and arrangement of the several parts, provided that such changes fall within the scope of the appended claims.

What I claim is:—

1. A device of the class described comprising a rear frame, a front frame hingedly connected at its lower end with the lower end of the rear frame and a pair of end pieces hingedly connected with the ends of the two frames, each end piece being composed of two sections hingedly connected

105

110

- together, a yoke-shaped member having the upper ends of its limbs hingedly connected with the lower end of the rear frame, a stem connected with the center of the top piece of 5 the rear frame and having an eye at its upper end for enabling the device to be hung on a projection extending from a wall and a latch hinged to the top piece of the rear frame for holding the parts in folded position.
- 10 2. A device of the class described comprising a rear frame composed of a rectangular member formed of wire and having an eye at each corner thereof, the lower eyes 15 being bent outwardly at right angles, horizontal and vertical wires having their ends connected with the rectangular member, a

front frame composed of an upper piece and two end pieces, the end pieces having eyes at their ends engaging the lower eyes of the 2 rear frame, vertical and horizontal wires connected with the front frame, with the lower ends of the vertical wires wrapped around the lower piece of the rear frame, a pair of end pieces connected with the ends 2 of the two frames, each end piece being formed of two sections which are hingedly connected together at the center of each end piece and a fastener for holding the device folded.

3 In testimony whereof I affix my signature.

ANDREW J. LIVESAY.
